UNITED STATES PATENT OFFICE.

CHARLES STREIFF, OF NEW YORK, N. Y.

DESIGN FOR A DISH.

SPECIFICATION forming part of Design No. 33,911, dated January 15, 1901.

Application filed December 20, 1900. Serial No. 40,594. Term of patent 3½ years.

To all whom it may concern:

Be it known that I, CHARLES STREIFF, a citizen of the United States, residing in the city of New York, borough of Manhattan, in the State of New York, have invented and produced a new and original Design for a Dish, of which the following is a specification, reference being had to the accompanying drawings, forming part thereof.

Figure 1 is a plan view of a dish, showing my new design; and Fig. 2 is a diametrical section thereof.

As shown in the drawings, the leading or material feature of my design consists of a scalloped rim ornamented with a beading of alternating pearl-like and elliptoid-like figures.

A indicates the scallops, and B and C, respectively, pearl-like and elliptoid-like figures which form the beading. Between each adjoining pair of elliptoid-like figures C is arranged a pair of pearl-like figures B, except at the corners or dents of the scallops, where there is but one of them.

What I claim is—

The design for a dish, as shown and described.

In testimony that I claim the foregoing as my invention I have signed my name in presence of two subscribing witnesses.

CHAS. STREIFF.

Witnesses:

GEO. L. WHEELOCK,
GEO. C. GEIBEL.
